UNITED STATES PATENT OFFICE.

WILLIAM ASHLEY KELLY, OF JERSEY CITY, NEW JERSEY, ASSIGNOR TO UNDERWOOD
TYPEWRITER COMPANY, OF NEW YORK, N. Y., A CORPORATION OF DELAWARE.

INVOICE SHEET.

Application filed November 12, 1920. Serial No. 423,556.

To all whom it may concern:

Be it known that I, WILLIAM ASHLEY KELLY, a citizen of the United States, residing in Jersey City, in the county of Hudson and State of New Jersey, have invented certain new and useful Improvements in Invoice Sheets, of which the following is a specification.

This invention relates to entry sheets for use in a typewriting machine, such, for example, as a bill-sheet or statement-sheet upon which successive items are entered from time to time or from day to day for a suitable period, commonly until the end of a month, when the completed statement is sent to the customer. Such sheets have been commonly provided with a detachable left-hand marginal part or lateral filing margin for temporarily binding or filing the entry sheet between the times of the typing of the successive entries or items thereon. This filing margin is torn off before sending the bill or statement to the customer, in order thereby to give a neat and pleasing appearance to the bill, particularly as the detachable filing margin is commonly provided with a plurality of large holes for use in the temporary filing or binding of the entry sheet.

By reason of the repeated insertion of the entry sheet into the typewriting machine, the top or leading edge thereof and particularly the upper corners have a tendency to become worn and frayed, so that by the time the end of the month is reached, the bill or statement is not in a neat or presentable condition for sending to the customer. This poor or damaged condition of the sheet has been in large part caused by the tendency of the corners at the top or leading end of the sheet to catch upon parts of the typewriting machine. Also, this catching of the corners interferes, of course, with the running of the sheets through the typewriting machine.

An important object of the invention is to facilitate the insertion in the typewriting machine of an entry sheet or statement sheet having a detachable filing margin, while leaving the entry-containing body part of the sheet in symmetrical shape for sending to the customer after the filing margin has been torn off. In this connection another object of the invention is to produce an entry sheet or statement-sheet

in which the part which is to be sent to the customer will not present fraying or other imperfection due to having been put through the typewriting machine many times.

According to the present invention, the entry sheet has rounded right and left upper corners, providing an upper end symmetrical in shape, and comprises a body part for receiving the successive items or entries, a detachable lateral marginal part providing for the temporary filing of the sheet between the times of making the successive entries, and a detachable narrow upper marginal part above and forming a leading end part of the entry sheet above the body part. The rounded right and left upper corners facilitate the passage of the entire width of the sheet (including said lateral marginal part) through the typewriting machine repeatedly. One of said rounded upper corners may be carried by the detachable filing marginal part and the other said rounded upper corner may be carried by the detachable upper marginal part. When both of said detachable marginal parts have been detached from the main or body part of the entry sheet this body part will be of pleasing symmetrical appearance for sending to the customer, and also this body part will be free from tearing, fraying or noticeable evidence of wear from having been passed repeatedly through the typewriting machine.

Other features and advantages will hereinafter appear.

In the accompanying drawing, the figure shown is a plan or face view of a bill-sheet or statement-sheet embodying the invention.

The statement-sheet or bill-sheet, illustrated in the accompanying drawing, comprises a main body part A, which, in this particular sheet, is shown as made up of an item-receiving lower part 1 upon which the various items may be successively entered, and an upper detachable stub part 2 to contain the customer's address and to be returned by him with his check, as has heretofore been customary. The stub part 2 is shown as joined to the entry-carrying part 1 by means of a line of perforations 3, as common heretofore. According to the present invention, there is provided above the stub part 2 of the body part A a narrow detachable upper marginal part 4 ex-

110

tending along the full width of the upper end of and forming a leading end part for the body part A, and joined to the upper stub part 2 thereof by means of a weakened 5 line of detachment, indicated in the drawing as a transverse line of perforations 5, whereby this leading end part 4 may be accurately and easily detached from the statement-forming body part A before the latter is sent to the customer.

The entry sheet is provided at the left side thereof with a filing margin or lateral marginal part 6 having therethrough large holes 7, shown as two in number, for convenience in temporarily binding or filing the entry sheet by this marginal side part 6, between the times of the making of the successive entries on the lower item-receiving part 1 of the body part A. This lateral 20 marginal part or filing margin 6 extends along the full length of the sheet and is joined to the main body part A, comprising the lower part 1 thereof and the upper part 2 thereof, by means of a vertical weakened 25 line of detachment, indicated in the drawing as a line of perforations 8, whereby the filing margin 6 may be accurately and easily detached from the body part A before sending the latter to the customer. The vertical 30 line of perforations 8 is shown as extended upward between the narrow top marginal part 4 and the upper end of the side marginal part 6, to the top edge or leading edge of the sheet, by means of a short vertical 35 line of perforations 9 forming an upward continuation of the line of perforations 8, so that the detachable upper marginal end part 4 and the detachable lateral filing marginal part 6 have an edge-to-edge overlapped relation defined by the short vertical 40 line of perforations 9, the lateral filing marginal part 6 at its upper end being coterminous with the upper marginal end part 4. The entry sheet is provided with right and 45 left upper blunt or rounded corners 10 and 11 carried respectively by the right end of the upper marginal end part 4 and by the upper end of the filing lateral margin 6. These rounded corners 10 and 11 facilitate 50 the repeated insertion of the sheet in the typewriting machine, and also co-operate with the upper marginal part 4 in protecting the upper end of the body part or statement part A from damage due to the repeated 55 passage of the sheet through the typewriting machine.

At the end of the month, when the entries on the sheet are complete, the tearing off of the left-hand margin or filing margin 6 along the vertical line of perforations 8 and 9 removes and does away with this now unnecessary, and more or less unsightly, marginal part. The tearing off of the narrow upper marginal part 4 along the transverse line of perforations 5 thereby removes

the original or initial leading edge of the sheet formed by this upper margin 4 which, by reason of repeated passing through the typewriting machine, may be to some extent worn or frayed, leaving a freshly-formed 70 and therefore perfect top edge on the body part A along the line of detachment 5. It is to be noted that the tearing off of the side margin 6 removes therewith the left upper rounded corner 11 but leaves the 75 right upper rounded corner 10 on the sheet, so that at this stage the sheet is left unsymmetrical, with one square and one rounded upper corner. However, the further tearing off of the top margin 4 removes there- 80 with the right upper rounded corner 10, and leaves the main body part A of the bill or statement of symmetrical outline, with two lower square corners and two upper square corners, thereby presenting a pleasing ap- 85 pearance. Also it will be evident that this main body part A, when sent to the customer, will still be in good condition without appreciable wear or other evidence of having been passed repeatedly through the 90 typewriting machine in making the various entries thereon.

Variations may be resorted to within the scope of the invention, and portions of the improvements may be used without others. 95

Having thus described my invention, I claim:

1. For use in a typewriting machine, an entry-sheet having rounded right and left upper corners for facilitating the insertion 100 of the sheet in the typewriting machine and a square lower right corner, and comprising a body-part provided with a heading space and vertical columns for having successive entries typed therein, a lateral filing marginal part at one side of the body-part detachably connected therewith along a weakened line providing for easy detachment of the filing marginal part from the body-part when the entries on the body-part are complete, and a waste marginal part on the body-part detachably connected therewith along a weakened line providing for easy detachment of said waste marginal part from the body-part when entries on the body-part are 110 complete, one of said upper rounded corners of the entry-sheet being formed upon the filing marginal part, and the other upper rounded corner of the entry-sheet being formed upon the waste marginal part, 115 whereby one of said rounded corners will be removed from the entry-sheet by the detachment of each of the marginal parts, so that the removal of both of the marginal parts will leave the entry-sheet in symmet- 120 rical shape with square corners.

2. For use in a typewriting machine, an entry-sheet having rounded right and left upper corners for facilitating the insertion 125 of the sheet in the typewriting machine and 130

a square lower right corner, and comprising a body-part including a heading space and a space divided into vertical columns for having successive entries typed therein, a 5 lateral filing marginal part at one side of the body-part detachably connected therewith throughout the length of the body-part along a weakened line providing for easy detachment of the filing marginal part from 10 the body-part when the entries on the body-part are complete, and an upper waste marginal part on the body-part detachably connected therewith along a weakened line providing for easy detachment of said upper 15 marginal part from the body-part when the

entries on the body-part are complete, one of said upper rounded corners of the entry-sheet being carried by the filing marginal part, and the other upper rounded corner of the entry-sheet being carried by the upper 20 marginal part, whereby one of said rounded corners will be removed from the entry-sheet by the detachment of each of the marginal parts, so that the removal of both of the marginal parts will leave the entry-sheet in a 25 symmetrical shape with square corners.

WILLIAM ASHLEY KELLY.
